UNITED STATES PATENT OFFICE

120,994

DESIGN FOR A GAME BOARD

Robert L. Lett, La Crosse, Wis.

Application March 19, 1940, Serial No. 91,076

Term of patent 7 years

To all whom it may concern:

Be it known that I, Robert L. Lett, a citizen of the United States, residing at La Crosse, in the county of La Crosse and State of Wisconsin, have invented a new, original, and ornamental Design for a Game Board, of which the following is a specification, reference being had to the accompanying drawing, forming part thereof.

I claim:

The ornamental design for a game board, as shown.

ROBERT L. LETT.
